**CASING FOR A VARIABLE RATIO TRANSMISSION
OR SIMILAR ARTICLE**

Vito Raso, Buena Park, Calif., assignor to Emerson Electric Co., a corporation of Missouri

Filed Nov. 19, 1963, Ser. No. 77,497

Term of patent 14 years

(Cl. D55—1)

Fig. 1.

Fig. 2.

Fig. 3.

FIG. 4.

FIG. 5.

FIG. 6.

FIG. 7.

FIGURE 1 is a front elevational view of a casing for a variable ratio transmission incorporating my new design;

FIG. 2 is a side elevational view thereof;

FIG. 3 is a top plan view thereof;

FIG. 4 is a rear elevational view thereof;

FIG. 5 is a side elevational view thereof, taken on the side opposite FIG. 2;

FIG. 6 is a rear elevational view thereof, showing the mounting bracket in an alternate position; and

FIG. 7 is a side elevational view as shown in FIG. 6, and showing the mounting bracket in an alternate position.

The motor structure and mounting base are illustrated in phantom lines to show environmental use.

I claim:

The ornamental design for a casing for a variable ratio transmission or similar article, substantially as shown and described.
